STAPLER

Harry O. Moore, Charlotte, N. C., assignor to Silabert Corporation, Charlotte, N. C., a corporation of North Carolina

Application January 24, 1957, Serial No. 44,585

Term of patent 14 years

(Cl. D74—1)

The dominant features of the design reside in the portion shown in full lines on the drawing.

I claim:

The ornamental design for a stapler, substantially as shown and described.
